UNITED STATES PATENT OFFICE.

HOWARD D. COLMAN, OF ROCKFORD, ILLINOIS.

KNOT-TYING IMPLEMENT.

SPECIFICATION forming part of Letters Patent No. 672,635, dated April 23, 1901.

Application filed February 20, 1901. Serial No. 48,117. (No model.)

To all whom it may concern:

Be it known that I, HOWARD D. COLMAN, a citizen of the United States, residing at Rockford, in the county of Winnebago and State of Illinois, have invented certain new and useful Improvements in Knot-Tying Implements, of which the following is a specification.

The object of this invention is the production of a hand-mounted power-driven knot-tying implement.

In the embodiment herein shown of this invention the tying mechanism is intended to be worn constantly on the left hand of the operator and its parts to be operated by power extraneous to the hand upon which it is mounted. A thumb-lever is adapted to operate a friction-clutch for engaging the knotter mechanism with the driving means and for disengaging it therefrom. After the knotter mechanism has been driven through the cycle of its movement a coil torsion-spring returns said mechanism to its normal or starting position.

The implement illustrated is adapted to tie spoolers' knots; and it comprises a rotatable tying-bill having a shearing and clamping jaw and a movable stripper for grasping the thread, drawing the knot tight, and pulling it from the tying-bill.

In the accompanying drawings, Figure 1 is a side elevation of a knot-tying implement embodying the features of my invention, showing the mechanism in the normal or starting position. Fig. 2 is a side elevation of said mechanism viewed from the side opposite from that shown in Fig. 1, the parts of the mechanism being in a normal position. Fig. 3 is a rear end elevation of this knot-tying implement with its parts in a normal position. Fig. 4 is a top plan view of the mechanism, showing the knotter-bill after it has made one-fourth of a revolution from the normal position and with the other parts of the mechanism in the positions relative thereto. Fig. 5 is a view similar to the preceding one, showing the knotter-bill after it has made three-fourths of a revolution from the normal position, the threads being represented as wound about said bill and the shearing and clamping jaw of the bill open to receive the threads. Fig. 6 is a view similar to those of

the two preceding figures, the knotter-bill being represented as having made one and one-fourth revolutions from its normal position, the threads having been cut off and clamped by the shearing and clamping jaw, and the knot being pulled from the knotter-bill by the thread-holding arm. Fig. 7 is a view of the stripper mechanism, showing it detached from the body of the implement. Fig. 8 is transverse section through the thread-holding arms E² and F, showing the spring-latch F⁵ and the surrounding parts in detail. Fig. 9 is a front end view of the cylinder which operates the shearing and clamping jaw. Figs. 10 and 11 are sectional detail views of the rotatable tying-bill and the cam-cylinder which operates the shearing and clamping jaw of said bill. Fig. 12 is a detail view showing in elevation the tying-bill and its cam-cylinder, it being represented in the position corresponding to that of Fig. 6, the threads being knotted over said tying-bill, the loose ends severed, and the knot about to be pulled from the bill by the stripper mechanism. Fig. 13 is an enlarged perspective view showing in detail the tying-bill. Fig. 14 is an enlarged view showing the position of the threads constituting the knot as the same is illustrated in Fig. 6. Fig. 15 is a view of a spooler's knot as formed by this mechanism.

Like letters of reference indicate corresponding parts throughout the several views.

In the construction of this implement I provide a standard A, having the integral overhanging arms A' at its upper end and the transverse sleeve A² at its lower end. A clip A³ surrounds said sleeve A² and is adapted to have frictional engagement with the outer surface of the transverse sleeve by means of the clamping-screw A⁴. The clip A³ has a downwardly-extending stem A⁵, intended to lie within a suitable opening in the handle A⁶ and to be held rigidly in position therein by the set-screw A⁷. The handle A⁶ is provided with a handle-strap A⁸ in loop form for surrounding the hand of the operator, and this loop is made adjustable in size in order to fit the hand of any person. I have shown a buckle for providing this adjustment, but any suitable means may be employed for this purpose. It will be noticed that the stem A⁵

may be turned with relation to the handle A⁶ and the sleeve A² in the clip A³ in order to secure an adjustment of the implement to accommodate it to hands of different forms.

5 A shaft B is free to oscillate within the sleeve A². At one end this shaft carries the collar B', fixed thereon, and between said collar and the clip A³ a coil torsion-spring B² is situated, said spring being mounted on the shaft B and its ends secured to the collar B' and the clip A³. The tendency of said torsion-spring is to oscillate the shaft B a certain distance in one direction, its purpose being to restore the knot-tying mechanism to its normal position after the driving power has operated it against the action of said spring. At the opposite end the shaft B carries the sector cam-gear B³, pinned to said shaft. The cam-groove B⁴ of the sector cam-gear is cut in the peripheral face of the sector, and the teeth of the gear are of skew-gear form. The cam-groove B⁴ is of an outline somewhat resembling that of the letter U, with its arms widespread and curved outward at their upper ends.

25 C is a knotted-shaft rotatably mounted in bearings formed in the overhanging arms A' of the standard A and carries the pinion C', the teeth of which are "skewed" to correspond with those of the sector cam-gear B³. The pinion C' is affixed to the shaft in any suitable manner. I have shown it as frictionally engaging said shaft, but it may be positively secured thereto in any desired way. 35 This pinion C' is provided with a long hub to occupy wholly the space upon the shaft C between the supporting-arms A', and thus prevent end movement of said shaft.

The forward end of the knotted-shaft C is 40 flattened on one of its sides and bent substantially at right angles to its length, forming the tying-bill C². The slot C³, its plane being parallel with that of the flattened surface of the tying-bill C², is formed in said bill and 45 said shaft C, and within said slot is pivotally mounted the shearing and clamping jaw C⁴. The lower part of this jaw is in wing form, adapted to engage the interior walls of the cam-cylinder C⁵, which latter is rigidly mounted on the standard A. This cam-cylinder is set eccentric to the knotted-shaft C, and its inner form is slightly elliptical in order to produce the proper movement of the shearing and clamping jaw C⁴, the wing of said jaw 50 engaging said internal cam. The flattened side of the tying-bill C² is provided with a shear edge within the slot C³, and the jaw C⁴, pivoted in said slot C³, with a corresponding shear edge. The opposite edge of said jaw is 55 rounded slightly, so that the latter will clamp while the opposite edge severs the ends of the threads in the tying-bill. A friction-disk C⁶ is fixed on the rear end of said knotted-shaft, being adapted to receive power to drive the 60 mechanism.

I have now described the mechanism for

forming the knot and cutting the thread. I will next describe the stripper mechanism.

A supporting-plate D is secured to the top of the standard A and is provided with the fixed forwardly-extending guide-arm D' for the thread. Rearward of the guide-arm D' is the vertical bearing-sleeve D², and near the opposite edge of the supporting-plate D is an upwardly-extending releasing-stud D³ for a purpose to be mentioned later herein. A stop-stud D⁴ at the forward edge of the supporting-plate limits the forward movement of the stripper mechanism. An oscillatory shaft E is adapted to lie within the vertical bearing-sleeve D², and this shaft carries the two crank-arms E' and E², fixed to said shaft. The former at the lower end of the shaft bears the antifriction-roller E³, adapted to lie within the cam-groove B⁴ of the sector cam-gear B³, and the latter at its outer end supports the pivotal arm E⁴, having the upwardly-extending thread-clamping fingers E⁵ fixed thereon. E⁶ is an engaging-stud mounted on the upper side of the crank-arm E², near the free end of said arm.

From the foregoing it will be seen that a movement of the sector-cam will produce a corresponding positive movement of the oscillatory shaft and the arms E² and E⁴.

F is a thread-holding arm loosely mounted by means of its integral ears F' on the oscillatory shaft E and having its outer portion F² bent at an angle with the plane of the body portion thereof. The forward end of the outer portion F² of said thread-holding arm is formed into a rearwardly-extending guide-arm F³ for the thread, between which arm and the fingers E⁵ the thread is clamped during the last part of the knot-tying operation, when the knot is being drawn tight and stripped from the tying-bill. The fingers E⁵ embrace the said outer portion F² of the thread-holding arm F, one finger lying on each side thereof. A spring F⁴, coiled about the oscillatory shaft E, is attached at its ends to the arm E² and the thread-holding arm F and by its elasticity tends to hold the said arms apart. The stop-stud D⁴ limits the forward movement of the thread-holding arm F, and the antifriction-roller E³ on the arm E', engaging the rear end of the cam-groove B⁴, forms a stop for the rearward movement of the arm E². A spring-latch F⁵ is pivotally mounted by the stud F⁶ on the thread-holding arm F and is adapted to engage the stud E⁶ on the arm E², and thereby hold the thread-holding arm F and the arm E² together, a spring coiled about the pivotal stud F⁶ tending to hold said latch in engagement with the stud. The latch F⁵ has an integral arm F⁷ extending substantially at right angles thereto, and a pin F⁸, fixed in said arm F⁷, extends downward through a slightly-elongated opening F⁹ in the thread-holding arm F into a position to be engaged by the upwardly-extending releasing-stud D³, which stud by delaying said pin rocks the latch F⁵ on its pivot

and withdraws it from its engagement with the stud E⁶. The pin F⁸ when so rocked is at the end of the elongated opening F⁹, and further rearward movement of the arm F is thus stopped. The arm E², however, moves rearward slightly farther to positively pull the fingers E⁵ from engagement with the guide-arm F⁸, between which fingers and arm the thread is wedged. When this is done, the spring F⁴ separates the arm E² and the thread-holding arm F, the former seeking its rear-most and the latter its foremost position. The guide-arm F⁸ is formed a little thicker than the thread-holding arm F, so that while the fingers E⁵ slide freely on the body of said arm they will tightly engage the guide-arm in order there to firmly grasp the thread.

The driving mechanism is supported upon a bracket G, fixed to the side of the standard A and extending rearward thereof. This bracket is provided with a transverse sleeve G' near its lower end. A rock-shaft G² is mounted in said sleeve, one end of which rock-shaft bears the thumb-lever G³, fixed to said shaft and extending forwardly therefrom to a point where its forward end is easily accessible to the thumb of the hand upon which the implement is mounted. The opposite end of the rock-shaft G² carries an upwardly-extending clutch-operating arm G⁴, also fixed to said shaft G². A longitudinally-movable shaft G⁵ is mounted in the bearing G⁶, integral with said bracket G, and at its forward end is provided with the rotatable friction-disk G⁷, fixed to said shaft, the clutch-operating arm G⁴ engaging the rear side of the hub of said friction-disk G⁷. This friction-disk has the usual leather face and coincides with the friction-disk C⁶, mounted on the knotter-shaft C. A collar G⁸ is fixed to the longitudinally-movable shaft G⁵, and between the bearing G⁶ on the bracket G and said collar is mounted a coil compression-spring G⁹, adapted to hold the friction-disk G⁷ from contact with the friction-disk C⁶. A flexible driving-shaft G¹⁰ is secured at one end to the longitudinally-movable shaft G⁵ and at the other carries the sheave G¹¹, by means of which shaft and sheave power is communicated to the shaft G⁵. A cord (not shown) running over said sheave G¹¹ furnishes power to drive said sheave and the flexible shaft.

In the operation of the implement the left hand of the operator is slipped within the handle-strap A⁸, the loop being adjusted to the size of the operator's hand, and the thumb of the operator placed upon the thumb-lever G³. Power is applied to rotate the flexible shaft G⁹, and the ends of the thread to be united, lying side by side, are drawn with the right hand of the operator over the outer end F² of the thread-holding arm F and the guide-arm D', and said arm and said guide

ing intermediately across the knotter-shaft C directly under the point of the tying-bill C². A downward pressure of the thumb upon the lever G³ moves the rotating friction-disk G⁷ into contact with the corresponding friction-disk C⁶, fixed to the knotter-shaft C. The knotter-shaft is rotated by the power thus applied and the sector cam-gear driven by reason of the skew-gear connection between said shaft and said sector-cam. The first quarter of a revolution of the tying-bill C² turns it into the position indicated in Fig. 4, the point of the tying-bill lying over the threads. During this quarter-revolution of the knotter-shaft the sector cam-gear B³ was moved, causing the roller E³ on the arm E' to travel outward a little distance in the cam-groove B⁴, oscillating the shaft E and moving forward the arm E² and the pivotal arm E' with its clamping-fingers E⁵, said fingers sliding forward, one on each side of the outer portion F² of the thread-holding arm F, also shown in Fig. 4 of the drawings. Continued oscillation of the cam continues the forward movement of the clamping-fingers E⁵ until, as the roller E³ reaches the lowest point in the cam-groove B⁴, the fingers E⁵ coincide with and embrace the outer end of the thread-holding arm F, clamping the thread between the fingers and the guide-arm F⁸. During the same time the stud E⁶ was moved into engagement with the spring-latch F⁵, locking the arm E² and the thread-holding arm F together, as shown by Fig. 5 of the drawings. At this point the tying-bill has been rotated through three-quarters of a revolution, and by reason of the interior conformation of the cam-cylinder C⁵ its shearing and clamping jaw C⁴ is open ready to receive the thread during the next quarter-revolution of said knotter-shaft. The continued rotation of the knotter-shaft throws the uptending or return side of the cam-groove B⁴ into contact with the roller E³, and as the tying-bill is turned into the position indicated in Fig. 6 the thread-holding arm F and the arm E² are thrown backward and outward, stripping the knot from the end of the tying-bill, the cam-surface within the cam-cylinder C⁵ having previously closed the shearing and clamping jaw C⁴ to cut off the threads and to hold the short ends thus formed while the knot is being stripped off the tying-bill by the backward movement of the clamping-fingers E⁵ in conjunction with the thread-holding arm F. When the tying-bill reaches the position indicated in Fig. 6, the ends of the thread will be pulled from the bill, and the pin F⁸, having now engaged the releasing-stud D³, further rearward movement of the arm E² causes the latch F⁵ to be disengaged from the stud E⁶ and the fingers E⁵ to be withdrawn from the guide-arm F⁸, whereupon the spring F⁴ throws the thread-holding arm into its forward position against the stop-pin D⁴. The thread is now free to be withdrawn, and the thumb-lever G³ is released, permitting the

- friction-disk G⁷ to be withdrawn from contact with the friction-disk C⁶. The power stored in the coil torsion-spring B² by the operative movement of the mechanism now restores said mechanism to its normal position, and during said restoring movement the mechanism is operated as just described, except that the knotter-bill is rotated in the opposite direction. The arm E² and the thread-holding arm F will be engaged and moved backward together until the pin F⁸ encounters the releasing-stud D⁸, when the latch F⁶ will release the stud E⁶, and the thread-holding arm F will be thrown into its forward or normal position by the spring F⁴. The rotation of the flexible shaft G¹⁰ and the friction-disk G⁷ should be moderately rapid. The thumb-lever G⁸ is depressed for an instant only, this being sufficient to permit the full operation of the tying mechanism. As soon as the pressure upon said lever is released the mechanism automatically assumes its normal position, ready to be operated again.
- I claim as my invention—
- 25 1. In a knot-tying implement, in combination, a knot-forming mechanism; means for securing said mechanism to the hand of the operator; and means for actuating said mechanism to form a knot.
  - 30 2. In a knot-tying implement, in combination, a knot-forming mechanism; means for securing said mechanism to the hand of the operator; and means adapted to be manually operated for actuating said knot-forming mechanism to form a knot.
  - 35 3. In a knot-tying implement, in combination, a knot-forming mechanism; means for securing said mechanism to the hand of the operator; and means adapted to be digitally operated, for actuating said knot-forming mechanism to form a knot.
  - 40 4. In a knot-tying implement, in combination, a knot-forming mechanism; means for securing said mechanism to the hand of the operator; and means adapted to be operated by a movement of the hand to which the implement is secured, for actuating said knot-forming mechanism to form a knot.
  - 45 5. In a knot-tying implement, in combination, a knot-forming mechanism; means for securing said mechanism to the hand of the operator; and means adapted to be operated by a movement of a digit of the hand to which the implement is secured, for actuating said knot-forming mechanism to form a knot.
  - 50 6. In a knot-tying implement, in combination, a knot-forming mechanism; means for securing said mechanism to the hand of the operator; and means adapted to be operated by a movement of the thumb of the hand to which the implement is secured, for actuating said knot-forming mechanism to form a knot.
  - 55 7. In a knot-tying implement, in combination, a knot-forming mechanism; means for securing said mechanism to the hand of the

operator; and a lever for actuating said knot-forming mechanism to form a knot.

8. In a knot-tying implement, in combination, a knot-forming mechanism; means for securing said mechanism to the hand of the operator; and a lever adapted to be operated by a movement of a digit of the hand to which the implement is secured, for actuating said knot-forming mechanism to form a knot. 75

9. In a knot-tying implement, in combination, a knot-forming mechanism; means for securing said mechanism to the hand of the operator; and a lever adapted to be operated by a movement of the thumb of the hand to which the implement is secured, for actuating said knot-forming mechanism to form a knot. 80

10. In a knot-tying implement, in combination, a knot-forming mechanism; means for securing said mechanism to the hand of the operator; and a pivoted arm adapted to be operated by a movement of the hand to which the implement is secured, for actuating said knot-forming mechanism to form a knot. 90

11. In a knot-tying implement, in combination, a knot-forming mechanism; means for securing said mechanism to the hand of the operator; means for driving said mechanism; and means for applying said driving means to operate said knot-forming mechanism. 95

12. In a knot-tying implement, in combination, a knot-forming mechanism; means for securing said mechanism to the hand of the operator; means for driving said mechanism; and means manually operated, for applying said driving means to operate said knot-forming mechanism.

13. In a knot-tying implement, in combination, a knot-forming mechanism; means for securing said mechanism to the hand of the operator; means for driving said mechanism; and means adapted to be digitally operated, for applying said driving means to operate said knot-forming mechanism. 105

14. In a knot-tying implement, in combination, a knot-forming mechanism; means for securing said mechanism to the hand of the operator; means for driving said mechanism; and means adapted to be operated by a movement of the hand to which the implement is secured, for applying said driving means to operate said knot-forming mechanism. 115

15. In a knot-tying implement, in combination, a knot-forming mechanism; means for securing said mechanism to the hand of the operator; means for driving said mechanism; and means adapted to be operated by a movement of a digit of the hand to which the implement is secured, for applying said driving means to operate said knot-forming mechanism. 120

16. In a knot-tying implement, in combination, a knot-forming mechanism; means for securing said mechanism to the hand of the operator; means for driving said mechanism; and means adapted to be operated by a move-

ment of the thumb of the hand to which the implement is secured, for applying said driving means to operate said knot-forming mechanism.

5 17. In a knot-tying implement, in combination, a knot-forming mechanism; means for securing said mechanism to the hand of the operator; means for driving said mechanism; and a lever adapted to be operated by a movement of a digit of the hand to which the implement is secured, for applying said driving means to operate said knot-forming mechanism.

10

18. In a knot-tying implement, in combination, a knot-forming mechanism; means for securing said mechanism to the hand of the operator; means for driving said mechanism; and a lever adapted to be operated by a movement of the thumb of the hand to which the implement is secured, for applying said driving means to operate said knot-forming mechanism.

19. In a knot-tying implement, in combination, a knot-forming mechanism; means for securing said mechanism to the hand of the operator; means for driving said mechanism; and a pivoted arm adapted to be operated by a movement of the hand to which the implement is secured, for applying said driving means to operate said knot-forming mechanism.

20. In a knot-tying implement, in combination, a rotatable tying-bill; means for securing said tying-bill to the hand of the operator; means for driving said tying-bill; and means manually operated, for applying said driving means to rotate said tying-bill.

21. In a knot-tying implement, in combination, a rotatable tying-bill; means for securing said tying-bill to the hand of the operator; means for driving said tying-bill; and means adapted to be digitally operated, for applying said driving means to rotate said tying-bill.

45 22. In a knot-tying implement, in combination, a rotatable tying-bill; means for securing said tying-bill to the hand of the operator; means for driving said tying-bill; and means adapted to be operated by a movement
50 of the hand to which the implement is secured, for applying said driving means to rotate said tying-bill.

28. In a knot-tying implement, in combination, a rotatable tying-bill; means for securing said tying-bill to the hand of the operator; means for driving said tying-bill; and means adapted to be operated by a movement of a digit of the hand to which the implement is secured, for applying said driving means to rotate said tying-bill.

24. In a knot-tying implement, in combination, a rotatable tying-bill; means for securing said tying-bill to the hand of the operator; means for driving said tying-bill; and
65 means adapted to be operated by a movement of the thumb of the hand to which the imple-

ment is secured, for applying said driving means to rotate said tying-bill.

25. In a knot-tying implement, in combination, a rotatable tying-bill; means for securing said tying-bill to the hand of the operator; means for driving said tying-bill; and a lever adapted to be operated by a movement of a digit of the hand to which the implement is secured, for applying said driving means to rotate said tying-bill. 75

26. In a knot-tying implement, in combination, a rotatable tying-bill; means for securing said tying-bill to the hand of the operator; means for driving said tying-bill; and a lever adapted to be operated by a movement of the thumb of the hand to which the implement is secured, for applying said driving means to rotate said tying-bill. 80

27. In a knot-tying implement, in combination, a rotatable tying-bill; means for securing said tying-bill to the hand of the operator; means for driving said tying-bill; and a pivoted arm adapted to be operated by a movement of the hand to which the implement is secured, for applying said driving means to rotate said tying-bill. 85 90

28. In a knot-tying implement, in combination, a knot-forming mechanism; means for securing said mechanism to the hand of the operator; a rotatable driving-shaft for operating said knot-forming mechanism; and means manually operated, for applying said driving-shaft to operate said knot-forming mechanism. 95

29. In a knot-tying implement, in combination, a knot-forming mechanism; means for securing said mechanism to the hand of the operator; a rotatable driving-shaft for operating said knot-forming mechanism; and means adapted to be digitally operated, for applying said driving-shaft to operate said knot-forming mechanism. 105

30. In a knot-tying implement, in combination, a knot-forming mechanism; means for securing said mechanism to the hand of the operator; a rotatable driving-shaft for operating said knot-forming mechanism; and means adapted to be operated by a movement of the hand to which the implement is secured, for applying said driving-shaft to operate said knot-forming mechanism.

31. In a knot-tying implement, in combination, a knot-forming mechanism; means for securing said mechanism to the hand of the operator; a rotatable driving-shaft for operating said knot-forming mechanism; and means adapted to be operated by a movement of a digit of the hand to which the implement is secured, for applying said driving-shaft to operate said knot-forming mechanism. 120 125

thumb of the hand to which the implement is secured, for applying said driving-shaft to operate said knot-forming mechanism.

33. In a knot-tying implement, in combination, a knot-forming mechanism; means for securing said mechanism to the hand of the operator; a rotatable driving-shaft for operating said knot-forming mechanism; and a lever adapted to be operated by a movement of a digit of the hand to which the implement is secured, for applying said driving-shaft to operate said knot-forming mechanism.

34. In a knot-tying implement, in combination, a knot-forming mechanism; means for 15 securing said mechanism to the hand of the operator; a rotatable driving-shaft for operating said knot-forming mechanism; and a lever adapted to be operated by a movement of the thumb of the hand to which the implement is 20 secured, for applying said driving-shaft to operate said knot-forming mechanism.

35. In a knot-tying implement, in combination, a knot-forming mechanism; means for securing said mechanism to the hand of the operator; a rotatable driving-shaft for operating said knot-forming mechanism; and a pivoted arm adapted to be operated by a movement of the hand to which the implement is secured, for applying said driving-shaft to operate said knot-forming mechanism.

36. In a knot-tying implement, in combination, a knot-forming mechanism; mechanism adapted to tighten the knot; means for securing said knot-forming mechanism and said knot-tightening mechanism to the hand of the operator; means for driving said mechanisms; and means manually operated, for applying said driving means to operate said knot-forming mechanism and said knot-tightening mechanism.

37. In a knot-tying implement, in combination, a knot-forming mechanism; mechanism adapted to tighten the knot; means for securing said knot-forming mechanism and said knot-tightening mechanism to the hand of the operator; means for driving said mechanisms; and means adapted to be digitally operated, for applying said driving means to operate said knot-forming mechanism and said knot-tightening mechanism.

38. In a knot-tying implement, in combination, a knot-forming mechanism; mechanism adapted to tighten the knot; means for securing said knot-forming mechanism and said knot-tightening mechanism to the hand of the operator; means for driving said mechanisms; and means adapted to be operated by a movement of the hand to which the implement is secured, for applying said driving means to operate said knot-forming mechanism and said knot-tightening mechanism.

39. In a knot-tying implement, in combination, a knot-forming mechanism; mechanism adapted to tighten the knot; means for securing said knot-forming mechanism and said knot-tightening mechanism to the hand of the operator; means for driving said mechanism.

isms; and means adapted to be operated by a movement of a digit of the hand to which the implement is secured, for applying said driving means to operate said knot-forming mechanism and said knot-tightening mechanism. 70

40. In a knot-tying implement, in combination, a knot-forming mechanism; mechanism adapted to tighten the knot; means for securing said knot-forming mechanism and said knot-tightening mechanism to the hand of the operator; means for driving said mechanisms; and means adapted to be operated by a movement of the thumb of the hand to which the implement is secured, for applying said driving means to operate said knot-forming mechanism and said knot-tightening mechanism. 75 80 85 90 95 98 99

41. In a knot-tying implement, in combination, a knot-forming mechanism; mechanism adapted to tighten the knot; means for securing said knot-forming mechanism and said knot-tightening mechanism to the hand of the operator; means for driving said mechanisms; and a lever adapted to be operated by a movement of a digit of the hand to which the implement is secured, for applying said driving means to operate said knot-forming mechanism and said knot-tightening mechanism. 90 95

42. In a knot-tying implement, in combination, a knot-forming mechanism; mechanism adapted to tighten the knot; means for securing said knot-forming mechanism and said knot-tightening mechanism to the hand of the operator; means for driving said mechanisms; and a lever adapted to be operated by a movement of the thumb of the hand to which the implement is secured, for applying said driving means to operate said knot-forming mechanism and said knot-tightening mechanism. 100 105

43. In a knot-tying implement, in combination, a knot-forming mechanism; mechanism adapted to tighten the knot; means for securing said knot-forming mechanism and said knot-tightening mechanism to the hand of the operator; means for driving said mechanisms; and a pivoted arm adapted to be operated by a movement of the hand to which the implement is secured, for applying said driving means to operate said knot-forming mechanism and said knot-tightening mechanism. 120

44. In a knot-tying implement, in combination, a knot-forming mechanism; a thread-holding mechanism adapted to clamp the thread and tighten the knot; means for securing said mechanisms to the hand of the operator; means for driving said mechanisms; and means manually operated, for applying said driving means to operate the knot-forming mechanism and to move the thread-holding mechanism relatively to the knot-forming mechanism. 125 130

45. In a knot-tying implement, in combination, a knot-forming mechanism; a thread-holding mechanism adapted to clamp the

thread and tighten the knot; means for securing said mechanisms to the hand of the operator; means for driving said mechanisms; and means adapted to be digitally operated, for applying said driving means to operate the knot-forming mechanism and to move the thread-holding mechanism relatively to the knot-forming mechanism.

46. In a knot-tying implement, in combination, a knot-forming mechanism; a thread-holding mechanism adapted to clamp the thread and tighten the knot; means for securing said mechanisms to the hand of the operator; means for driving said mechanisms; and means adapted to be operated by a movement of the hand to which the implement is secured, for applying said driving means to operate the knot-forming mechanism and to move the thread-holding mechanism relatively to the knot-forming mechanism.

47. In a knot-tying implement, in combination, a knot-forming mechanism; a thread-holding mechanism adapted to clamp the thread and tighten the knot; means for securing said mechanisms to the hand of the operator; means for driving said mechanisms; and means adapted to be operated by a movement of a digit of the hand to which the implement is secured, for applying said driving means to operate the knot-forming mechanism and to move the thread-holding mechanism relatively to the knot-forming mechanism.

48. In a knot-tying implement, in combination, a knot-forming mechanism; a thread-holding mechanism adapted to clamp the thread and tighten the knot; means for securing said mechanisms to the hand of the operator; means for driving said mechanisms; and means adapted to be operated by a movement of the thumb of the hand to which the implement is secured, for applying said driving means to operate the knot-forming mechanism and to move the thread-holding mechanism relatively to the knot-forming mechanism.

49. In a knot-tying implement, in combination, a knot-forming mechanism; a thread-holding mechanism adapted to clamp the thread and tighten the knot; means for securing said mechanisms to the hand of the operator; means for driving said mechanisms; and a lever adapted to be operated by a movement of a digit of the hand to which the implement is secured, for applying said driving means to operate the knot-forming mechanism and to move the thread-holding mechanism relatively to the knot-forming mechanism.

50. In a knot-tying implement, in combination, a knot-forming mechanism; a thread-holding mechanism adapted to clamp the thread and tighten the knot; means for securing said mechanisms to the hand of the operator; means for driving said mechanisms; and a lever adapted to be operated by a movement of the thumb of the hand to which the

implement is secured, for applying said driving means to operate the knot-forming mechanism and to move the thread-holding mechanism relatively to the knot-forming mechanism.

51. In a knot-tying implement, in combination, a knot-forming mechanism; a thread-holding mechanism adapted to clamp the thread and tighten the knot; means for securing said mechanisms to the hand of the operator; means for driving said mechanisms; and a pivoted arm adapted to be operated by a movement of the hand to which the implement is secured, for applying said driving means to operate the knot-forming mechanism and to move the thread-holding mechanism relatively to the knot-forming mechanism.

52. In a knot-tying implement, in combination, a knot-forming mechanism; mechanism adapted to tighten the knot; means for securing said knot-forming mechanism and said knot-tightening mechanism to the hand of the operator; means for driving said mechanisms; a clutch for applying said driving means to operate said knot-forming mechanism and said knot-tightening mechanism; and means for operating said clutch.

53. In a knot-tying implement, in combination, a knot-forming mechanism; mechanism adapted to tighten the knot; means for securing said knot-forming mechanism and said knot-tightening mechanism to the hand of the operator; means for driving said mechanisms; a clutch for applying said driving means to operate said knot-forming mechanism and said knot-tightening mechanism; and a lever for operating said clutch.

54. In a knot-tying implement, in combination, a knot-forming mechanism; a thread-holding mechanism adapted to clamp the thread and tighten the knot; means for securing said mechanisms to the hand of the operator; means for driving said mechanisms; a clutch for applying said driving means to operate said knot-forming mechanism and to move the thread-holding mechanism relatively to the knot-forming mechanism; and means for operating said clutch.

55. In a knot-tying implement, in combination, a knot-forming mechanism; a thread-holding mechanism adapted to clamp the thread and tighten the knot; means for securing said mechanisms to the hand of the operator; means for driving said mechanisms; a clutch for applying said driving means to operate said knot-forming mechanism and to move the thread-holding mechanism relatively to the knot-forming mechanism; and a lever for operating said clutch.

56. In a knot-tying implement, in combination, a tying-bill; means for rotating said tying-bill; one member of a clutch for said tying-bill; an oscillatory shaft; a thread-holding arm loosely mounted on said shaft, but capable of being held with relation thereto, which arm is adapted to clamp the thread and move away from the tying-bill to draw

up the slack in the thread to tighten the knot and pull the thread from said tying-bill; means for releasably holding said thread-holding arm with relation to said oscillatory shaft so it will rotate therewith, and for releasing said arm from movement with said shaft; a driving-shaft having a clutch member adapted to engage with the clutch member for the tying-bill; and means for engaging said clutch members.

57. In a knot-tying implement, in combination, a tying-bill; means for rotating said tying-bill; one member of a clutch for said tying-bill; an oscillatory shaft; a thread-holding arm loosely mounted on said shaft, but capable of being held with relation thereto,

which arm is adapted to clamp the thread and move away from the tying-bill to draw up the slack in the thread to tighten the knot and pull the thread from said tying-bill; means for releasably holding said thread-holding arm with relation to said oscillatory shaft so it will rotate therewith, and for releasing said arm from movement with said shaft; a driving-shaft having a clutch member adapted to engage with the clutch member for the tying-bill; and a lever for engaging said clutch members. 20 25
